UNITED STATES PATENT OFFICE.

RALPH L. FORD, OF CHICAGO, ILLINOIS, ASSIGNOR, BY MESNE ASSIGNMENTS, TO
INTERNATIONAL HARVESTER COMPANY, A CORPORATION OF NEW JERSEY.

LEVER MECHANISM.

1,366,565.

Specification of Letters Patent. Patented Jan. 25, 1921.

Application filed May 27, 1918. Serial No. 236,935.

To all whom it may concern:

Be it known that I, RALPH L. FORD, a citizen of the United States, residing at Chicago, in the county of Cook, and State 5 of Illinois, have invented certain new and useful Improvements in Lever Mechanism, of which the following is a full, clear, and exact specification.

This invention relates to lever mechanism, 10 and more particularly to the type of lever mechanism used in connection with agricultural machines, such, for instance, as planters.

In operating machines of this character 15 wherein a supplemental frame such as a furrow opener frame is hinged to the main frame of the machine, it is desirable at times to adjust the supplemental or furrow opener frame to a fixed position with relation to the main frame, and at other times 20 to allow the furrow opener frame or auxiliary frame to float with respect to the main frame.

In order to accomplish these results it is 25 necessary that lever mechanism be provided which can be adjusted to such a position as to hold the two frames in definite fixed relation with respect to each other, and which can also be manipulated in such a manner 30 that the two frames will be free to move independently of each other.

The object of the present invention is 35 to provide mechanism whereby these two conditions may be fulfilled, namely, means for maintaining fixed adjustment between the two frames, and means whereby the two frames may float with respect to each other.

With these objects in view my invention 40 is embodied in a lever construction wherein means are provided for locking the lever in a fixed position of adjustment, and means are also provided for rendering the locking means inoperative and for holding the 45 locking means in inoperative position.

I have disclosed one embodiment of my invention in the accompanying drawings, and in these drawings,—

Figure 1 shows a side elevation of the improved lever mechanism;

Fig. 2 is an end view of Fig. 1;

Fig. 3 is an enlarged view in section, showing the construction of the lever and locking pawl;

Fig. 4 is an enlarged view of the pawl 55 construction; and

Fig. 5 is an enlarged view of the pawl lifting member.

The lever 10 is bifurcated at its lower end and is pivoted at 11 to a fixed sector 12, 60 which in turn is secured to the frame 13 of the machine by suitable securing means 14. The lever is provided with the usual locking pawl 15 which is slidably carried by a casing 16 and is under normal conditions raised and lowered by means of the usual thumb lever 17 pivoted to the lever and connected to the pawl by a link 18. The casing 16 is secured to the lever 10 at its lower bifurcated portion by means of a 70 bolt 19, and at its upper end has portions 20 which overlap the rear portion of the lever and secure the casing in position thereon. This casing is also provided with an inwardly projecting portion 21 received in 75 a slot 22 of the pawl 15, the pawl being guided in its movement by the side walls of the casing and by the projection 21. The pawl 15 in its normal position coacts with the usual notches 26 formed in the upper 80 surface of the sector, and secures the lever in a fixed position of adjustment with relation to the sector.

The means for rendering the pawl inoperative and for holding it in inoperative 85 position will now be described.

A cam lifting member 23 is pivoted on the bolt 19 in the bifurcated lower end of the lever, and the front end of this cam lifting member 25 extends forwardly through 90 the slot 22 of the pawl 15 and has a downwardly extending portion 24 which normally contacts with the front wall of the casing and limits the rearward movement of the member 23. This lifting member has at its rear end a 95 weighted projection 25 which normally holds the member in the position shown in full lines in Fig. 1. When it is desired to lock the pawl in inoperative position in order that the lever may float with respect 100 to the sector, the operator lifts sliding pawl 15 by pressing thumb lever 17 and then by a quick forward thrust of lever 10 cam member 23 will be rotated on bolt 19 to the forward position as shown in dotted lines 105 in Fig. 1. The pawl will be retained in this position until the operator presses the thumb lever, raising pawl 15 and by a quick

thrust of lever 10 rearwardly, causes the cam member to rotate rearwardly. The lifting member will thereupon again assume the position shown in full lines and 5 the pawl will drop into the registering notch on the sector 12. As an alternative method of raising and locking the pawl, as when it is not convenient for the operator to shift the lever 10 by hand, the lifting member 23 10 may be thrust forward by foot pressure or by raising the ball 25 whereupon the cam surface of the member by reason of its engagement with the top of the slot 22 will raise the pawl 15 and hold it in inoperative 15 position. The cam surface on the lifting member is so designed that the lifting member will be retained in its dotted line position by the weight of the pawl until it is positively released. If desired, a spring 27 20 may be used to force the pawl 15 into its lower position in engagement with notches 25 and as shown in the drawings, the spring engages projection 21 at one end and the lower end wall of slot 22 at the 25 other end. The spring 27 also assists in holding the pawl 15 in engagement with the cam surface on the lifting member in the dotted line position shown in Fig. 1.

While I have in the above specification described one embodiment which my invention may assume, it should be understood that the invention is capable of modification and that modifications may be employed without departing from the spirit and scope of the 35 invention as expressed in the following claims:

1. In a lever mechanism, the combination of a lever, a toothed sector, locking means carried by the lever and adapted to engage 40 the sector to lock the lever in fixed position, means for actuating the locking means, and means controlled by said lever for rendering said locking means inoperative.

2. In a lever mechanism, the combination 45 of a lever, means for locking said lever in a fixed position of adjustment, and means controlled by the movement of said lever for rendering said locking means inoperative and for holding the locking means in inop- 50 erative position.

3. In a lever mechanism, the combination of a lever, means including a pawl for locking said lever in a fixed position of adjustment, and means pivoted on said lever and 55 operatively connected with said pawl for rendering said pawl inoperative by a movement of said lever and for holding the pawl in inoperative position.

4. In a lever mechanism, a sector, a lever 60 having a bifurcated lower end, the bifurcations being disposed on the opposite sides of said sector, a slidable pawl mounted on said lever and adapted to coöperate with said

sector, and means pivoted to said lever and disposed between the bifurcations of the 65 lower end of said lever for engaging said pawl and rendering said pawl inoperative.

5. In a lever mechanism, a sector a lever having a bifurcated lower end, the bifurcations being disposed on the opposite sides of 70 said sector, a slotted pawl carried by said lever and adapted to coöperate with said sector and a cam member pivoted on said lever between the bifurcations of said lever and engaging the slot in said pawl for ren- 75 dering said pawl inoperative.

6. In a lever mechanism, the combination of a lever, means including a reciprocable pawl for locking said lever in a fixed position of adjustment, and a cam member pivoted to 80 said lever and operatively connected to said pawl for rendering said pawl inoperative and for holding the pawl in inoperative position.

7. In a lever mechanism, the combination 85 of a lever, means including a slotted pawl for locking said lever in a fixed position of adjustment, and pivoted means carried by said lever and extending through the slot in said pawl for rendering the pawl inopera- 90 tive.

8. In a lever mechanism, the combination of a lever, means including a slotted pawl for locking said lever in a fixed position of adjustment, and a cam member pivoted to 95 said lever and extending through the slot in said pawl for rendering the pawl inopera- 90 tive.

9. In a lever mechanism, the combination of a lever, means including a pawl for locking 100 said lever in a fixed position of adjustment, a cam member operatively connected to said pawl for rendering said pawl inoperative, said cam member having means for limiting the movement thereof in one direc- 105 tion.

10. In a lever mechanism, the combination of a lever, means for locking said lever in a fixed position of adjustment, a cam member 110 operatively connected to said locking means for rendering the locking means inoperative, said cam member having means for normally holding the same in a predetermined position of adjustment.

11. In a lever mechanism, the combination 115 of a lever, means for locking the lever in a fixed position of adjustment, a cam member for rendering said locking means inoperative, said cam member having a portion for limiting the movement thereof in one direc- 120 tion, and having another portion for normally holding the same in a predetermined position of adjustment.

In testimony whereof I affix my signature.

RALPH L. FORD.
